ROTARY TABLE MACHINE FOR PACKING
BOTTLES AND THE LIKE

Morris P. Neal, Quincy, Ill., assignor to A-B-C
Packaging Machine Corporation, Quincy, Ill., a
corporation of Illinois

Application July 10, 1947, Serial No. 760,138

20 Claims. (Cl. 226—14)

1

The present invention relates generally to packaging machines, and more particularly to a packaging machine which packs bottles, and other individual container units and articles, in inverted positions in cartons or other containers, and to a method of packing bottles, and the like, in inverted positions in containers.

There has long existed, in the packaging machinery art, the need for a packaging machine which will commercially successfully load bottles, and the like, in inverted positions in cartons or other containers. It is highly advantageous to pack empty bottles neck down in containers, for then when emptied therefrom at the place of use all of the bottles are upright on the particular receiving surface and ready for the first step of whatever process may be at hand. Bottle manufacturers have long sought after a packaging machine which will commercially thus package empty bottles neck down in containers, particularly one in which the loss due to bottle breakage in packaging is substantially eliminated.

Therefore, an object of the present invention is to provide a novel packaging machine which incorporates the features long sought after in the art as essential in such a machine for packing bottles, and other articles, in inverted positions in containers.

Another object is to provide a novel method of packing bottles, and the like, in cartons and other containers in which the bottles, and the like, are disposed in inverted positions.

Another object is to provide a novel packaging machine which is particularly adapted to pack bottles neck down in cartons rapidly and with substantially no bottle breakage.

Another object is to provide a novel packaging machine particularly adapted for loading bottles in cartons in which a predetermined number of assembled bottles are covered by an upside-down carton and the grouped bottles and covering carton rotated through substantially one hundred and eighty degrees to dispose the bottles in upside-down position in a right-side-up carton.

Another object is to provide a novel packaging machine which packages bottles in upside-down positions in cartons which is fully automatic through each cycle.

Another object is to provide a novel packaging machine for loading bottles in upside-down positions in cartons which incorporates bottle grouping mechanism which automatically functions to group only a predetermined number of bottles.

Another object is to provide a novel packaging

2

machine for loading bottles in upside-down positions in cartons which incorporates novel rotary table mechanism for receiving and for rotating a group of assembled bottles and a covering upside-down carton from one plane through one hundred and eighty degrees to a lower plane, which operation effects position reversal of bottles and carton, and, hence, upside-down loading of the bottles in the carton.

Another object is to provide a novel packaging machine for loading bottles in upside-down positions in cartons which incorporates novel discharge conveyor mechanism for receiving loaded cartons and for automatically unloading received cartons onto the floor or onto an adjacent receiving device.

Another object is to provide a novel packaging machine incorporating a rotatable table mechanism for inverting bottles, and the like, in containers which includes novel indexing mechanism for automatically indexing the table mechanism every one hundred and eighty degrees of rotation.

Another object is to provide a novel packaging machine which packs bottles into containers in inverted positions without dropping them, thereby reducing to a minimum damage to the bottles and the containers and increasing the overall packing yield.

Other objects and advantages are to provide a novel packaging machine for loading bottles, or the like, in inverted positions in containers which is rugged in construction, thereby insuring long use with a minimum of maintenance, which packages at a rapid rate, which requires only a single attendant, and which is adapted to be operated by an attendant with maximum efficiency after only a little instruction.

The foregoing and other objects and advantages are apparent from the following description taken with the accompanying drawings, in which:

Fig. 1 is a diagrammatic plan view of a packaging machine constructed in accordance with the teachings of the present invention, shown in conjunction with a diagrammatically indicated empty carton conveyor and a bottle supplying conveyor (Sheet 1);

Fig. 2 is a diagrammatic side elevational view thereof, the associated bottle supply conveyor being omitted (Sheet 1);

Fig. 3 is a diagrammatic end view thereof, the associated bottle supply and empty carton conveyor being omitted (Sheet 1);

Fig. 4 is a wiring diagram illustrating the wiring layout incorporated in a preferred embodiment of the present packaging machine (Sheet 1);

Fig. 5 is a side elevational view of a packaging machine incorporating the concepts of the present invention, an associated inverted carton being shown in cross section to better illustrate details (Sheet 2);

Fig. 6 is a plan view thereof, the grouped bottles on the transverse continuous belts and the covering carton being omitted, additional bottles being shown approaching the push-off positions (Sheet 3);

Fig. 7 is a side elevational view thereof at 180° to Fig. 5, a portion of the bottle feeding conveyer and its support being broken away for conservation of space (Sheet 4);

Fig. 8 is an enlarged end view of the free end of the bottle feeding mechanism including the supporting head (Sheet 3);

Fig. 9 is an enlarged vertical transverse cross-sectional view on substantially the line 9—9 of Fig. 6 (Sheet 3);

Fig. 10 is an enlarged vertical transverse cross-sectional view on substantially the line 10—10 of Fig. 6 (Sheet 3);

Fig. 11 is a longitudinal vertical cross-sectional view on substantially the line 11—11 of Fig. 8 (Sheet 4);

Fig. 12 is a vertical transverse cross-sectional view substantially on the line 12—12 of Fig. 5 (Sheet 5);

Fig. 13 is a vertical longitudinal cross-sectional view taken on approximately the line 13—13 of Fig. 12 (Sheet 6);

Fig. 14 is an enlarged fragmentary plan view of a central portion of the machine showing, in particular, in one extreme position of movement, details of the bottle limit switch construction, the pusher mechanism, the bottle guide mechanism, and related elements (Sheet 7);

Fig. 14a is an enlarged vertical longitudinal cross-sectional view through a switch arm shown in Fig. 14 (Sheet 7);

Fig. 15 is an enlarged fragmentary plan view similar to Fig. 14, showing the other position of movement of the several said mechanisms (Sheet 8);

Fig. 16 is an enlarged fragmentary longitudinal view through half of the bottle receiving rotary table mechanism and the loaded carton receiving and discharge conveyer mechanism, a bottle loaded carton being illustrated as received by the latter mechanism from the former mechanism, the loaded carton receiving and discharge conveyor mechanism being shown in collapsed carton unloading position in broken lines (Sheet 9);

Fig. 17 is a fragmentary further enlarged plan view of the timer mechanism and a portion of the pusher mechanism (Sheet 6);

Fig. 18 is a vertical cross-sectional view on the line 18—18 of Fig. 17 (Sheet 6);

Fig. 19 is a vertical cross-sectional view on the line 19—19 of Fig. 17 (Sheet 6);

Fig. 20 is an enlarged fragmentary elevational view showing in greater detail a portion of Fig. 12, particularly illustrating the relationship of the clutch for the transverse continuous belts of the rotary table mechanism and the rack member for rotating the belts (Sheet 5);

Fig. 21 is a view of the clutch shown in Fig. 20, with the cover plate removed (Sheet 5);

Fig. 22 is a vertical cross-sectional view on the

line 22—22 of Fig. 20, showing details of the rack member adjustable stop (Sheet 5);

Fig. 23 is a further enlarged cross-sectional view on the line 23—23 of Fig. 20, showing details of the clutch, rack and pinion, and a portion of one of the continuous belts (Sheet 9);

Fig. 24 is an enlarged side elevational view of the contact end of the rack member for actuating the transverse belts (Sheet 5);

Fig. 25 is an end elevational view thereof (Sheet 5);

Fig. 26 is a plan view of the loaded case-receiving conveyor (Sheet 5);

Fig. 27 is an enlarged plan view of one of the pivot arms which forms part of the loaded case-receiving and discharge conveyor mechanism (Sheet 9);

Fig. 28 is an enlarged plan view, partly in section, of the conveyer lift casting (Sheet 4);

Fig. 29 is a side elevational view thereof (Sheet 4);

Fig. 30 is an enlarged vertical transverse cross-sectional view on the line 30—30 of Fig. 5 (Sheet 10);

Fig. 31 is an enlarged vertical transverse cross-sectional view on the line 31—31 of Fig. 5 (Sheet 10);

Fig. 32 is an enlarged vertical transverse cross-sectional view on the line 32—32 of Fig. 5 (Sheet 10);

Fig. 33 is an enlarged isometric view showing details of the indexing mechanism (Sheet 10);

Fig. 34 is an enlarged plan view, partly in section, of the locating pin operating arm which forms part of the indexing mechanism (Sheet 10);

Fig. 35 is a plan view of the indexing ratchet wheel (Sheet 3);

Fig. 36 is a side elevational view, partly in section, of the locating pin, an element of the indexing mechanism (Sheet 3);

Fig. 37 is a side elevational view thereof at 90° to Fig. 36 (Sheet 3);

Fig. 38 is an enlarged fragmentary horizontal cross-sectional view through a portion of the switch bar and supported elements forming part of the bottle limit switch construction (Sheet 7);

Fig. 39 is a plan view of the bottle stop (Sheet 7);

Fig. 40 is a side elevational view thereof (Sheet 7);

Fig. 41 is a fragmentary enlarged plan view of one end of the pusher plate and associated elements forming part of the pusher mechanism (Sheet 7);

Fig. 42 is a vertical cross-sectional view through a portion of the bottle guide mechanism taken on substantially the line 42—42 of Fig. 14 (Sheet 7);

Fig. 43 is an isometric view of the timer solenoid trip device (Sheet 10);

Fig. 44 is a plan view, partly in section, of the casting which forms the central element of the rotary table mechanism (Sheet 11);

Fig. 45 is a cross-sectional view on the line 45—45 of Fig. 44 (Sheet 11);

Fig. 46 is a vertical cross-sectional view on the line 46—46 of Fig. 45 (Sheet 11);

Fig. 47 is a plan view of one of the intermediate dividing plates of the rotary table mechanism (Sheet 11);

Fig. 48 is a plan view of the outside plate of the rotary table mechanism (Sheet 11);

Fig. 49 is a plan view of a ratchet wheel forming part of the indexing mechanism (Sheet 11);

Fig. 50 is an edge elevational view thereof (Sheet 11);

Fig. 51 is a plan view of the timer ratchet wheel (Sheet 11);

Fig. 52 is an edge elevational view thereof (Sheet 11);

Fig. 53 is an edge elevational view of the timer limit wheel (Sheet 11);

Fig. 54 is a plan view thereof (Sheet 11);

Fig. 55 is a plan view of the timer ratchet stop pawl (Sheet 11);

Fig. 56 is a plan view of a mechanism which may be installed in the bottle feeding line for limiting the number of bottles supplied to the present case packer per unit of operating cycle (Sheet 8);

Fig. 57 is a side elevational view thereof (Sheet 8);

Fig. 58 is a horizontal cross-sectional view on the line 58—58 of Fig. 57 (Sheet 8); and

Fig. 59 is a vertical cross-sectional view on the line 59—59 of Fig. 57 (Sheet 8).

Referring to the drawings more particularly by reference numerals, 70 indicates generally a bottle, or the like, packaging machine, or case packer, constructed in accordance with the concepts of the present invention.

Broadly, the present case packer 70 includes a frame 71, bottle feeding mechanism 72 including a continuously running belt (Figs. 5 and 6), a pusher mechanism 73 (Figs. 14 and 15), bottle guide mechanism 74 (Figs. 12, 14, 15 and 42), bottle limit switch construction 75 (Figs. 13-15 and 38), a bottle stop 76 (Figs. 13-15, 39 and 40), a timer mechanism 77 for limiting the number of rows of bottles admitted for assembly as a group per cycle (Figs. 12 and 17 through 19), a rotary table mechanism 78 for receiving in a group a predetermined number of bottles, or the like, and for disposing the assembled group in a carton, or the like, in inverted positions (Figs. 5, 6, 15, 16, 23 and 44 through 47), an indexing mechanism 79 for rotating the table mechanism 78 through 180° at a predetermined point in the operation cycle (Figs. 5, 13, 30 through 34), a carton guide 80 (Figs. 5 and 16), and a loaded case receiving and discharge conveyer mechanism 81 (Figs. 7, 12, 13, 16 and 26-29), together with coordinating elements, both mechanical and electrical. The several mechanisms, constructions and devices broadly set forth above are more particularly described in detail below.

The frame 71 includes a vertical front plate 85 and a rear vertical plate 86, which are securely connected together in opposed relation by two lower tie rods 87 and two upper tie rods 88 (Figs. 5, 7, 12 and 13). Bolts 89 and 90 extend through the plates 85 and 86 into internally threaded wells in the ends of the tie rods 87 and 88, respectively. Each plate 85 and 86 includes vertical side flanges 91, a top flange 92 and a bottom flange 93, which strengthen the plates and form supports for elements more particularly referred to below (Figs. 12 and 13). To the lower outer face of the frame plate 85 are welded or otherwise secured two spaced composite frames 94 on which are disposed boards 95 serving as a platform for an attendant.

The bottle feeding mechanism 72 includes a stand 96 comprising a base plate 97, reinforcing fins 98, a post 99, and a top plate 100 threadedly secured to the post 99, thereby permitting adjustment (Figs. 5, 6 and 8 through 13). Two short angle bars 103 are secured by bolt assemblies 104 to the top of the plate 100 in opposed relation. A

vertical plate 105 is secured against the outer face of the upright flange of each angle bar 103, being anchored in place by the rear end of an elongated strap 106 abutting the lower edge thereof and bolts 107 which extend through the strap 106, the plate 105, and threadedly engage the vertical flange of the angle bar 103. The strap 106 is welded at 108 to the upper face of the plate 100. The forward end of each strap 106 is secured by suitable bolts 109 to the upper end of a short angle bar 110 secured by bolts 111 to a plate 112 anchored by suitable bolts 113 to the flanges 91 of the frame plates 85 and 86 (Figs. 5 and 12).

An idler sprocket 116 is freely mounted between the plates 105 on a stationary shaft 117 (Figs. 9 and 11). The shaft 117 extends through rectangular openings 118 in the plates 105 and has support at each end in a pair of small plates 119 which span the opening 118 of each plate 105 and are secured together in adjusted position in respect thereto by nut and bolt assemblies 120 (Fig. 5). The sprocket 116 has bearing support on a bushing 121 and is spaced centrally of the interior small plates 119 by spacer collars 122. An adjustment nut 124 is mounted eccentrically on each end of the shaft 117 outwardly of the outer small plate 119 and includes a threaded bore which receives the threaded end of an elongated bolt 126. Each bolt 126 also extends through an aperture provided in the outwardly extending flange of an angle bracket 127 secured to the plate 105 by welding 128 (Fig. 5). It is manifest that the position of the idler sprocket 116 may be adjusted lengthwise of the bolts 126 by rotating the bolts 126 in the direction desired after loosening the nut and bolt assemblies 120. After the proper adjustment is secured, the nut and bolt assemblies 120 are retightened to maintain the attained adjustment.

Extending through openings in the upper inner corners of the plates 105 for support is a shaft 130 secured against removal by suitable nuts 131 (Figs. 5, 9 and 10). The outer ends of two elongated conveyor chain supporting members 132 are supported by the shaft 130 which extends through suitable openings in each. The members 132 are spaced from each other by a sleeve 133 and from the inner faces of the plates 105 by collars 134. A link plate conveyer chain 136 rests on the supporting members 132, as is clear from Figs. 5 and 10, and travels around the idler sprocket 116, the teeth of which engage transverse lugs 137 of the links of the chain 136. The other ends of the supporting members 132 are supported by a suitable supporting arm 140 which extends inwardly from the top flange 92 of the frame plate 86 (Fig. 13). The other end of the chain 136 engages a driven sprocket 142 keyed to a shaft 143 rotatively mounted on a suitable bracket 144 secured by bolts 145 to the inner face of the frame plate 86.

Power for the power driven sprocket 142 is provided in the form of an electric motor 147 (Fig. 7), mounted on a plate 148 secured by suitable bolts 149 to the outer face of the frame plate 86. To the rotor shaft of the motor 147 is secured a pulley 150, about which is trained an endless drive belt 151, the belt 151 also being trained around a driven pulley 152 mounted on a shaft 153 extending from a speed reduction transmission generally indicated at 154. No details of the speed reduction transmission 154 are given since it is of standard construction and any type may be employed. Power is taken from the transmission 154 by a shaft 155 to which is se-

cured a large sprocket 156 (Figs. 7 and 12). A continuous chain 157 engages the sprocket 156 and a smaller sprocket 158 secured to the shaft 143. The transmission 154 includes the usual adjustment device for varying its output in order to regulate the travel speed of the chain 136 as desired. It is to be observed that the return segment of the chain 136 travels between the spaced straps 166 which form a guard therefor.

Spaced bottle guide straps 162 are secured to the upper ends of small plates 163 mounted in upright position on the supporting members 132, suitable bolts 164 being used for both securing purposes. A bottle actuated switch 165 is secured to one of the guide straps 162 (Figs. 5 and 6), and includes a pivotally mounted actuating arm 166 which extends into the path of bottles traveling on the bottle conveyer chain 136. The switch 165 may be of any make-and-break type, the contacts being separated to break the circuit therethrough when the arm 166 is in the position shown in Fig. 6. The electrical hook-up of the switch 165 and the motor 147 is more particularly considered below in connection with the description of Fig. 4 and of the over-all operation of the machine 10.

For moving bottles 170, or the like, from the bottle conveyer chain 136 as a predetermined number thereof, six in the present machine 10 selected as illustrative reach predetermined positions in respect to the rotatively mounted table mechanism 78, the pusher mechanism 73, above mentioned in the general description, is provided (Figs. 6, 7, 12 through 15, 17 and 41). Supporting the pusher mechanism 73 are two spaced brackets 171, which may be of the form shown in Figs. 7 and 12 and which are secured to the outer face of the frame plate 86 by suitable bolts 172. The brackets 171 extend upwardly from the upper edge of the frame plate 86, and each includes a horizontal flange 173 to which is anchored a plate 174 by suitable bolts 175.

Two pairs of spaced bearing brackets 177 are secured to the plate 174 by suitable bolts 178. One pair of bearing brackets 177 slidably receives a pusher shaft 179, and the other pair of brackets 177 slidably receives a pusher shaft 180. To the forward end of each of the pusher shafts 179 and 180 is secured a pusher shaft bracket 183 (Figs. 14, 15 and 17) which supports a bottle pusher plate 184 through suitable bolts 185, a pusher attachment bar 186 being disposed between the brackets 183 and the pusher plate 184. A bottle guiding strip 187 is secured to the top of the attachment strip 186 by screws 188 and extends forwardly therefrom. At its bottle receiving end, the pusher plate 184 includes a right angularly rearwardly directed flange 189 (Fig. 15) which prevents bottles 170 from moving behind the pusher plate 184 during the brief time it is in its forward position.

Power means for reciprocating the pusher shafts 179 and 180, together with their supported pusher plate 184, includes a solenoid operated air motor 191 mounted on and anchored to the plate 174 by suitable nut and bolt assemblies, or the like, between the pusher shafts 179 and 180. The air motor 191 is of any standard commercial construction, including a solenoid 190 for opening its air valve, usually spring actuated to reverse the air, and, therefore, detailed description thereof is omitted as unnecessary. The air motor 191 includes a reciprocating rod 192, to the free end of which is secured a bracket 193 (Fig.

15)... The bracket 193 is secured by bolts, or the like, to the pusher attachment bar 186 midway between the brackets 183. The electrical connections to the solenoid 190 for energization and deenergization thereof are more particularly described below in conjunction with the description of Fig. 4.

The bottle stop 76 is mounted on the pusher mechanism 73 for reciprocation therewith (Figs. 10 through 15, 39 and 40). As is clear from Figs. 39 and 40, the bottle stop 76 includes a central bearing sleeve 195 to which are welded, or otherwise fixed, angularly disposed arms 196 and 197. The free end of the arm 196 is bifurcated and rotatably receives a roller 198 mounted on a rivet 199, or the like. The arm 197 may be a strap member and is formed with an arcuate free end portion 200, the radius of which may be substantially that of the commercial short beer bottle. The bottle stop 76 is pivotally mounted between two strap members 201 secured as by welding to an extension at one edge of the pusher plate 184, as is clear from Figs. 13 and 15, the bearing sleeve 195 being received on a suitable shaft having secured support in the strap members 201. The roller 198 tracks along the vertical flanges of two angularly disposed angle members 204 and 205 secured by suitable screws, or the like, to the bottom face of the plate 174, being biased into constant engagement therewith by a tension spring 206, one end of which is connected to the arm 196 and the other end to the extension of the pusher plate 184. It is manifest that the bottle stop 76 moves from its bottle stopping position, as is shown in Fig. 14, to its inoperative position, as is shown in Fig. 15, through tracking of the angle members 204 and 205 by the roller 198 under the influence of the spring 206 as the pusher plate 184 is moved forwardly.

At the other side of the pusher mechanism 73 remote from the bottle stop 76 is the timer mechanism 77 for limiting through a mechanical count the number of rows of bottles assembled on the table mechanism 78 (Figs. 12, 14 and 17 through 19). The timer mechanism 77 is supported on the plate 174 and includes an upstanding bracket 210 of the form shown secured to the plate 174 by suitable bolts extending through a horizontal base flange 211 thereof. Welded or otherwise secured to an upper edge of the bracket 210 is a horizontal solenoid plate 212 which supports a timer reset solenoid 213 of conventional plunger type secured thereto by suitable screws 214, or the like. The solenoid 213 includes a plunger 215, to the free outer end of which is pivotally connected at 216 a link 217. To the other end of the link 217 at 218 is pivotally connected a ratchet stop pawl 220. The ratchet stop pawl 220 is pivotally mounted intermediate its ends on the bracket 210 by means of a pivot post 221. At its free end, the pawl 220 is formed as a hook 222 for engagement with certain teeth 223 of a ratchet wheel 224 (Figs. 51 and 52) secured as by setscrews to a shaft 225 rotatably mounted in a bushing supported by the bracket 210. A tension spring 228 anchored to the bracket 210 at one end and to the pawl 220 at the other end biases the pawl 220 into engagement with the ratchet wheel 224, as is clear from Fig. 18.

A timer ratchet pawl 230, in the form of an elongated strap, is pivotally mounted at one end on a bolt 231 supported by the reduced end of the pusher shaft 180, the pawl 230 being spaced

from the shaft 180 by a spacer sleeve 232 and secured on the end of the bolt 231 by a suitable screw 233, or the like (Fig. 14). Toward its forward end, the pawl 230 has sliding support on a guide member 235 of spool configuration, which is mounted on the plate 210 for support. A leaf spring 236 secured to the solenoid plate 212 by a suitable screw 237, or the like, biases the pawl 230 into engagement with the guide member 235. Forwardly of the guide member 235, the pawl 230 includes a hook portion 239, which is adapted to engage certain teeth of the ratchet wheel 224. It is to be noted that the thickness of the ratchet wheel 224 is sufficient to accommodate both the ratchet stop pawl 220 and the timer ratchet pawl 230. It is clear that, every time the pusher mechanism 73 completes a cycle, the ratchet pawl 230 reciprocates, and, through its hook portion 239, rotates the ratchet wheel 224 a distance of one tooth, the stop pawl 220 preventing return rotation of the ratchet wheel 224 while the ratchet pawl 230 is reciprocating.

Below the solenoid 213 and supported on the outer face of the bracket 210 is a limit switch 240 of standard construction which includes a moving switch blade and two stationary contacts. There is provided a plunger 241 for actuating the switch 240, the free end of which is bifurcated and rotatively supports a small roller 242. The plunger 241 is spring biased into its extended position, as is shown in Fig. 19. For pushing the plunger 241 inwardly, there is provided a timer limit wheel 244, which is secured to the shaft 225 by suitable setscrews 245, or the like. As is clear from Figs. 53 and 54, the limit wheel 244 includes a finger 246 extending from the periphery thereof slightly off a radius which may be integral with or secured to the wheel 244 by welding. As is clear from Figs. 17 and 19, the finger 246 engages the roller 242 for inward movement of the plunger 241 as the fourth tooth of the ratchet wheel 224 is brought into the position occupied by the first tooth thereof in Figs. 18 and 19. Hence, four rows of bottles 170 may be pushed onto the rotary table mechanism 78 by the pusher mechanism 73 before the limit switch 240 is actuated. Extending outwardly from one face of the wheel 244 is a lug 247 which is adapted to strike an adjustment screw 248 threadedly mounted in a threaded aperture of a lug 249 welded or otherwise secured to the bracket 210 and extending outwardly from the outer face thereof. The lug 247 and the adjustment screw 248 limit counterclockwise movement of the wheel 244, as viewed in Fig. 19, and, hence, of the ratchet wheel 224.

Near its free end, the stop pawl 220 carries a lift pin 251 which extends beneath the ratchet pawl 230, as is clear from Figs. 17 and 18. Hence, when the solenoid 213 is energized to draw its plunger 215 inwardly or to the right, as in Figs. 18 and 19, the stop pawl 220 is pivoted clockwise to release its hook portion 222 from engaging relation with the teeth of the ratchet wheel 224, the lift pin 251 functioning during this pivotal action of the stop pawl 220 to lift the ratchet pawl 230 from engagement with the ratchet wheel 224. With both the stop pawl 220 and the ratchet pawl 230 released from engagement with the ratchet wheel 224, the ratchet wheel 224 returns to the starting position shown in Figs. 18 and 19 under the influence of a suitable spring (not shown), the lug 247 and adjustment screw 248 cooperating to limit the counterclockwise return movement of the ratchet wheel 224.

For energizing and deenergizing the solenoid 75

213 in timed relation with the indexing of the rotary table mechanism 78, there is provided a simple push type on-and-off switch 252 secured to and beneath the conveyer chain supporting member 132 adjacent the forward side of the rotary table mechanism 78, viewing Fig. 12. The switch 252 includes a plunger 253 carrying at its end a roller 254 which in indexed position of the rotary table mechanism 78 is disposed between two trip plates 255 of a trip device 256 secured to an outside plate (more particularly referred to by reference numeral below) of the rotary table mechanism 78 through suitable screws 257 (Fig. 43). There is a trip device 256 secured to each of the two end plates of the rotary table mechanism 78. Succinctly, as the rotary table mechanism 78 begins its rotary movement, the roller 254 mounts the trip plate 255 moving past, thereby forcing the plunger 253 inwardly to close the switch 252 and energize the solenoid 213. The solenoid 213 remains energized and effective until the roller 254 is tripped a second time by the passing trip plate 255 of the trip device 256 on the other outside plate of the rotary table mechanism 78 just prior to indexing of the mechanism 78, which de-energizes the solenoid 213. The electric circuits including the solenoid 213, the switch 240 and the switch 252 are particularly set forth below in the description of Fig. 4.

30 The bottle guide mechanism 74 is provided for insuring an upright position of the bottles 170 as they are moved into position for action of the pusher mechanism 73 (Figs. 12, 14, 15 and 42). The bottle guide mechanism 74 includes a shaft 260 which is pivotally mounted at one end in the vertical flange of a bracket 261 and at the other end in a bushing supported in the upper end of the timer bracket 210. At each end of the shaft 260 is an adjustment block 262 which slidably receives the free ends of a U-shaped bottle guide member 263. Suitable setscrews 264 provide for adjustment of the guide member 263 in respect to the adjustment blocks 262. As is clear from Figs. 12 and 14, the bight portion of the guide member 263 is bent downwardly in respect to the main portion of the legs in order to engage the bottles 170 near the tops thereof. The particular form of the guide member 263 shown permits the bottles 170 to pass freely by the leg member thereof.

50 Adjustably secured to the shaft 260 intermediate the ends thereof are two spaced trip members 266, each having a trip finger 267 (Figs. 14 and 42). Setscrews 268, or the like, maintain the trip members 266 in selected positions on the shaft 260. Associated with each finger 267 is a pusher shaft 269 mounted for guided reciprocative movement in a guide sleeve 270 secured to the air motor 191 for support. The end of each 55 of the pusher shafts 269 remote from the fingers 267 is secured to a bracket 271, which is in turn secured to the plunger of the solenoid 190 of the air motor 191. It is clear that movement of the plunger of the solenoid 190 from the position of Fig. 14 to the position of Fig. 15 effects lifting of the guide member 263 from engagement with the bottles 170 through sliding movement of the pusher members 269 and rotation of the shaft 260 caused by engagement of the free ends of the pusher members 269 with the fingers 267 of the trip members 266. Since the solenoid 190 actuates the air motor 191, the guide member 263 will be lifted prior to pushing action of the pusher mechanism 73, and will be returned to bottle

guiding position upon return of the plunger of the solenoid 190 to starting position.

The bottle limit switch construction 75 is provided for initiating operation of the pusher mechanism 73 and related mechanisms, more particularly described below, after a predetermined number of bottles 170 has been moved to position for transverse travel from the chain 136 to the rotary table mechanism 78 (Figs. 13 through 15 and 38). The limit switch construction 75 includes an elongated switch bar 275 having six spaced openings 276 therethrough (Fig. 38). Mounted adjacent each opening 276 between upper and lower spaced integral flanges 277 is a make-and-break switch 278 of the plunger actuated type, each switch 278 being secured in place by a strap 279 fastened by screws 280 to the flanges 277. Each switch 278 includes terminal strips 282 extending from each end thereof and a plunger 283 for making and breaking the circuit through the terminal strips 282. Connecting the adjacent terminal strips 282 are conductor strips 284 mounted on insulation blocks 285 secured to the switch bar 275 by screws 286. The conductor strip 284 associated with each of the outer switches 278 is connected to a terminal post 287 for connecting the switches 278 into an operating circuit more particularly referred to below in conjunction with the description of Fig. 4.

A finger member 290 is pivotally mounted on a pin 291 supported in and spanning each of the openings 276. Each finger 290 includes a cam 292 which cooperates with the plunger 283 of its respective adjacent switch 278 to force the same inwardly upon movement of the finger 290 clockwise as viewed in Fig. 38. A block 294 is secured to the bar 275 adjacent each opening 276 by a suitable screw 295. An adjustment screw assembly 296 is threadedly mounted in each block 294. A tension spring 297 has one end secured to the block 294 and the other end to the finger 290, thereby biasing the finger 290 into engagement with the free end of the adjustment screw 296. Manifestly, the rest positions of the fingers 290 are determined by the positions of the adjustment screws 296, each of which may be readily independently adjusted as desired. The switch bar 275 with its aforesaid elements is supported by two spaced brackets 298 (Fig. 14), the foot of each of which is secured to the plate 174.

It is to be understood that the circuit between the terminal strips 282 of each switch 278 is open when the plunger 283 is extended, as shown in Fig. 38, and is closed when the plunger 283 is forced inwardly by the cam 292 of the respective finger 290. The switches 278 are in series and, therefore, all six switches 278 must be closed for current to flow between the terminals 287. In the circuit of the six switches 278 is a switch 300 of the two fixed contacts and movable switch blade type, from which extends a rotatable operating arm 301 (Figs. 14, 14a, and 15). The arm 301 projects into the path of a trip finger 302 forming part of a trip member 303 adjustably secured to the pusher shaft 179. The arm 301 is hollow and includes a spring extended plunger 304 beveled at 304' to permit the trip finger 302 to pass the plunger 304 on the return movement of the pusher mechanism 73 by camming the plunger 304 inwardly. The switch blade of the switch 300 normally engages the fixed contact in series with the switches 278, the arm 301 being in the position shown in Fig. 15. When the arm 301 is rotated clockwise by the trip finger 302,

the circuit of switches 278 is broken and a holding circuit is completed which remains effective until the arm 301 returns under spring action to its normal position. The circuits of the switch 300 are set forth below in the description of Fig. 4.

The rotatably mounted table mechanism 78 is disposed in relation to the pusher mechanism 73 and the chain 136 for receiving rows of bottles from the chain 136; in the present disclosure, four rows of six bottles each comprising a case load (Figs. 5, 6, 14 through 16, 23 and 44 through 47). A heavy shaft 305 is pivotally mounted in suitable bearings formed integral with or supported in the frame plates 85 and 86 (Fig. 32). A table casting 306 of the form clearly shown in Figs. 44 through 46 is mounted on the shaft 305 for rotation therewith. The casting 306 includes a central body portion 307 having an opening 308 therethrough for mounting on the shaft 305. Threaded apertures 309 are provided for the reception of suitable setscrews for preventing longitudinal movement of the casting 306 along the shaft 305. A keyway 310 is also provided which receives a key 311 (Fig. 16) for securing the casting 306 to the shaft 305 for rotation therewith. The casting 306 is symmetrical about a longitudinal center line and includes three arms 314 extending outwardly from each side thereof. Spaced bifurcated posts 315 extend upwardly from the arms 314 and from the body portion 307 to define six upper and lower passageways 316, viewing Fig. 45. An outside plate 317 (Figs. 14 and 48) is secured to each end of the casting 306 by suitable bolts 318 (Fig. 12), which extend through openings 319 in each plate 317 and into suitable threaded wells 320 in the ends of each of the arms 314 of the casting 306. An intermediate plate 321 (Fig. 47) is mounted in the bifurcations of each aligned set of three posts 315 (Fig. 14), being secured to a plate 322 at the rear edge thereof by welding, or the like, the plate 322 being secured to the plates 317 by welding or the like.

Each plate 317 includes two spaced openings 325 (Fig. 48), each opening 325 of each plate 317 receiving a bearing member 326 (Fig. 23) secured in place by suitable screws 327. Each bearing member 326 has a bushing 328. Rotatably mounted in aligned pairs of bushings 328 is a shaft 330. It is to be observed that the two shafts 330 are disposed transversely of the shaft 305 and equi-distant therefrom. At one end of each of the shafts 330 is an overrunning clutch 332 (Figs. 20, 21 and 23), which may be of any type allowing counterclockwise movement as viewed in Fig. 20. The clutch 332 illustrated includes a casing 333 freely rotatably mounted on a bushing 334 disposed about the shaft 330. Inferiorly of the casing 333 and relatively rotatable in respect thereto is a clutch member 335 of the form shown in Fig. 21, including inclined surfaces 336 and shoulders 337. Roller bearings 338 are provided which are disposed between retaining rings 339. A closure plate 340 is secured to the casing 333 by suitable screws 341. The clutch member 335 is keyed to the shaft 330 by a suitable key 342 disposed in keyways 343 and 344 provided in the shaft 330 and the clutch member 335, respectively. A pinion 347 is secured to the neck portion of the casing 333 by a suitable key 348 for rotation therewith. A rack member 350 engages the pinion 347 through teeth 351 for movement thereof. It is clear that counterclockwise movement of the pinion 347 (con-

sidering Figs. 20 and 21) will effect counterclockwise movement of the shaft 330 since the pinion 347 is keyed to the casing 333, and the clutch 332, of which the casing 333 is a part, will effect positive counterclockwise movement of the shaft 330 through the elements aforesaid. Free movement to the right of the rack 350 is permitted by the clutch 332.

Six rollers 355 are secured to each shaft 330 by suitable setscrews 356 (Fig. 23), there being a roller disposed between each pair of intermediate plates 321 and between each outside plate 317 and the opposite intermediate plate 321 (Fig. 6). The outside plates 317 and the intermediate plates 321 support vertically spaced shafts 360 which have bearing support in the two spaced openings 361 in the outside plates 317 and the openings 362 in the intermediate plates 321 (Figs. 14, 47 and 48). Each shaft 360 supports for free rotation six small rollers 363, there being one opposite each roller 355. A flexible continuous or endless belt 364 is trained about each pair of opposed rollers 355 and 363. There are, therefore, six belts 364 in a horizontal plane above the main shaft 305, and six in a horizontal plane below. A plurality of belt supporting shafts 366 are supported in openings 367 in the outside plates 317 and extend beneath the belts 364 (Figs. 14, 20 and 48). Each shaft 366 carries six sleeves or rollers freely rotatable thereon, one beneath each belt 364. Seven such assemblies are shown for each plane of belts 364, although a greater or lesser number may be employed as the circumstances warrant. An idler roller 369 (Figs. 12 and 20) is provided for each belt 364, the idler rollers 369 being freely mounted on a shaft 370 which extends through vertically elongated openings 371 in the outside plates 317. An adjustment screw 372 bears against each outer end of each shaft 370 for maintaining the idlers 369 in engagement with the belts 364. Each adjustment screw 372 has threaded support in a bracket 373 secured to the plate 317 by suitable bolts 374.

Four carton guide fingers 380 (Figs. 6, 12 and 16) are provided above each set of belts 364, being welded or otherwise secured to the upper edges of the outside plates 317. Also secured as by welding to the outside plates 317 and to the plate 322 are carton flap or ear holders 381 (Figs. 12 and 16). As is clear from Fig. 12, no holder 381 is provided for the ear of the carton along the chain 136, since the flap or ear will snugly fit alongside the row of bottles 170 on the chain 136 ready for the next action of the pusher mechanism 73. The relationship of a carton 382 and its usual separators 383 to the holders 381 and the fingers 380 is clearly shown in Figs. 12 and 16.

Each rack 350 is formed at its end remote from the teeth 351 with an offset button 386 (Figs. 24 and 25), and is supported by spaced bracket strips 387 secured to the outside plate 317 by suitable bolts 388 (Fig. 20). A stop member 390 (Fig. 22) is adjustably secured on the rack 350 by suitable setscrews 391. One end of a tension spring 392 (Fig. 12) is secured to the stop member 390 by a suitable screw 393, the other end being secured to the plate 317. The tension spring 392 biases the rack 350 to the position in Fig. 12, the right-hand bracket strip 387 forming an abutment against which the stop 390 strikes.

Power means is provided for moving the operatively disposed rack 350 to the left, considering Fig. 12, in the form of a solenoid actuated air motor 397 (Figs. 12 and 14). The air motor 397

is mounted on a bracket 398 secured by welding, or the like, to the frame plate 86. The air motor 397 includes a plunger 399 which is aligned with the button 386. A solenoid 400, when energized, opens the valve of the air motor 397 to effect movement of the plunger 399 outwardly. The solenoid operated air motor 397 is of standard construction and, hence, further description is unnecessary. The circuit of the solenoid 400 is described in detail below in the description of Fig. 4. The details of the mechanism for rotating the rotary table mechanism 78 are set forth below in the description of the indexing mechanism 79.

The case guide 80 (Figs. 5, 6 and 16) is disposed adjacent the table mechanism 78 and includes an arcuate metal plate 405 substantially concentric with the axis of rotation of the rotary table mechanism 78. As is clear from Fig. 5, the plate 405 extends upwardly to substantially the top of the upside down carton 382 disposed over the bottles 170 on the rotary table mechanism 78. The plate 405 is welded or otherwise secured to a shaft 406 supported by spaced brackets 407 mounted atop the frame plates 85 and 86. Suitable setscrews 408 secure the shaft 406 in removable position on the brackets 407. Near its lower end, the plate 405 rests on the left-hand upper tie rod 88 as viewed in Fig. 16.

The indexing mechanism 79 is provided for rotating the rotary table mechanism 78 through one hundred and eighty degrees of rotation at a predetermined point in the case loading cycle in order to remove a group of assembled bottles 170, or the like, from assembled position into a carton 382 in neck down positions and to dispose the table mechanism 78 for further assembly of bottles 170 with minimum loss of time (Figs. 5, 6, 12, 13 and 30-35). The shaft 305 of the rotary table mechanism 78 has a reduced portion 411 at the right end when viewing Fig. 12, which carries keyed thereto a small gear 412 (Figs. 12 and 13). Meshing with the gear 412 is a large gear 413 which is mounted on a suitable stub shaft 414 supported by the frame plate 86 (Fig. 7). A ratchet wheel 416 is secured to the large gear 413 for rotation therewith by suitable bolts, or the like, which extend through openings 417 provided in the ratchet wheel 416 (Fig. 49) and into the inner face of the gear 413. The ratchet wheel 416 is provided with eight equi-spaced shoulders 418. A ratchet crank arm 420 is rotatably mounted on the inner end of the stub shaft 414 adjacent the inner face of the ratchet wheel 416 (Fig. 13) and pivotally supports adjacent its outer free end a pawl 421 biased by a tension spring 422 into engagement with the periphery of the ratchet wheel 416, one end of the spring 422 being secured to the pawl 421 and the other end to an edge of the ratchet crank arm 420.

For power actuation of the crank arm 420, there is provided a standard commercial solenoid operated air motor 425 actuated by a solenoid 424, said air motor 425 being pivotally mounted at 426 on a bracket 427 secured by suitable bolts 428 to the plate 112 (Figs. 12 and 13). The air motor 425 includes a piston rod 429 which threadedly or otherwise receives on its end to permit adjustment an extension member 430 which is pivotally connected at 431 to the crank arm 420 intermediate the ends thereof. It is manifest that a power stroke of the piston rod 429 of the air motor 425 will effect rotation of the shaft 305 through the several elements just described. It is to be understood that the

ratio of the gears 412 and 413 and the stroke of the piston rod 429 are correlated to effect a rotation of one hundred and eighty degrees of the shaft 305 upon each power stroke of the air motor 425. A normally open make-and-break switch 432 is mounted on the frame plate 85 near the gear 413 and includes a resiliently biased arm 433 extending into the path of movement of the crank arm 420 (Fig. 13). The arm 433 is rotated by the crank arm 420 to close the switch 432 as the piston rod 429 of the air motor 425 reaches the end of its power stroke. The electrical circuit of the switch 432 is detailed below in the description of Fig. 4.

An indexing locating ratchet wheel 435 is keyed to the shaft 305 for rotation therewith adjacent the frame plate 85 and remote from the small gear 412 (Figs. 5, 6, 12, 32, 33 and 35). Setscrews 436 extend through suitable threaded openings in the hub thereof to prevent axial displacement. The ratchet wheel 435 includes two diametrically opposed shoulders 437 and two diametrically opposed openings 438. A locating pin 440 is mounted in a bushing 441 press fitted or otherwise secured in an opening through an enlarged block-shaped bearing portion 442 formed integral with or secured to the frame plate 85 (Figs. 5, 6, 32, 36 and 37). The locating pin 440 includes a head 443 having a channel 444 therein. As is manifest from the drawings, the locating pin 440 successively engages the opening 438 in the locating ratchet wheel as they align therewith in the indexing rotation of the table mechanism 78.

A locating pin operating arm 447 (Figs. 6, 32 and 34) is provided for withdrawing the locating pin 440 from securing the locating ratchet wheel 435 against rotation which includes a main arm 448, an enlargement 449 at one end thereof, an apertured bearing hub 450 at the other end, and an opening 451 in the arm 448 intermediate the ends. Extending radially from the hub 450 is a post 452, and threaded setscrew openings 453 are provided in opposed position. The operating arm 447 is mounted on a vertical rotatably mounted shaft 455 through the medium of the hub 450. Setscrews 456 (Fig. 30) secure the operating arm 447 to the shaft 455 for rotation therewith. A post 457 is pivotally mounted at 458 (Fig. 6) in the opening 451 of the operating arm 447, the post 457 extending through a suitable opening in the frame plate 85 and carrying on its free end a compression spring 459 which abuts at one end the inner face of the frame plate 85 and at the other end a suitable washer anchored to the post 457, thereby biasing the operating arm into the position of Figs. 6 and 32, in which the locating pin 440 engages an opening 438 in the locating ratchet wheel 435. It is clear from the drawings that the enlargement 449 engages in the channel 444 of the locating pin 440, and that clockwise pivotal movement of the operating arm 447, as viewed in Fig. 6, effects withdrawal action of the pin 440.

The shaft 455 is pivotally mounted in spaced bearing brackets 461 adjacent the upper end thereof and a bearing bracket 462 adjacent the lower end thereof (Fig. 5), the former brackets being secured to the outer face of the frame plate 85 by suitable bolts 463 and the latter by suitable bolts 464. It is to be observed that the lower end of the shaft 455 is reduced at 465, and that this reduced portion 465 is received by the bearing bracket 462 in a manner to support the shaft 455 against downward movement.

A locating pawl 468 is pivotally mounted on a stud 469 supported by the bearing portion 442 of the frame plate 85, a suitable nut 470 engaging the threaded free end thereof to maintain the stud 469 in place (Figs. 5, 32 and 33). The free end of the pawl 468 normally engages one of the shoulders 437 of the locating ratchet wheel 435. Welded or otherwise secured to the pawl 468 is a bracket 471 which supports a coupling member 472, the latter including a reduced extension 473 which is peened over or otherwise secured in an opening formed in the bracket 471. A connecting shaft 474 is pivotally connected at 475 to the coupling 472 at one end and at the other end is pivotally connected at 476 to a coupling 477 of the same form as the coupling 472. The coupling 477 includes a reduced extension 478 (Fig. 30) which extends through an opening in the vertical flange of a bracket 479 and is peened over to secure the coupling 477 thereto. The bracket 479 is welded or otherwise secured to a hub member 480 pivotally mounted on the shaft 455. Setscrews 481 secure the hub 480 to the shaft 455 for rotation therewith. A spacing collar 482 separates the hub 480 from the hub 450. A tension spring 483 biases the free end of the pawl 468 into engagement with the periphery of the ratchet wheel 435, one end thereof being connected to a post 484 anchored in the connecting shaft 474 and the other end to a pin 485 anchored in the frame plate 85 (Fig. 5). It is manifest from the foregoing that rotation of the shaft 455 effects pivotal action of the pawl 468 counterclockwise, as viewed in Fig. 5, to withdraw its free end from engagement with the shoulder 437 of the ratchet wheel 435 and that, upon release of the shaft 455, the spring 483 will return the free end of the pawl 468 to engagement with the periphery of the ratchet wheel 435 to insure contact with the next shoulder 437. As is indicated in Fig. 32, space is provided between the connecting shaft 474 and the bight of the U-shaped opening of the coupling members 472 and 477, so that pivotal action between the couplings 472 and 477 and the connecting shaft 474 may be effected.

Power means for rotating the shaft 455 clockwise, when viewed in Fig. 6, is provided in the form of a standard commercial solenoid actuated air motor 487 including a solenoid 488, the air motor 487 being mounted on the outer face of the frame plate 85 and also including a plunger 489 (Fig. 5). The plunger 489 has adjustably threaded on the free end thereof a bifurcated member 490 which is pivotally connected to an ear 491 welded or otherwise secured to the shaft 455 for rotation therewith. For energizing the solenoid 488 and initiating the indexing sequence there is provided a normally open make-and-break switch 492 closed by a push button 493 and mounted on the outer bracket 407 (Fig. 5). The electrical circuit of the solenoid 488 and the switch 492 is detailed below in the description of Fig. 4.

Two switches 494 and 495 are mounted on the inner face of the frame plate 85 in vertical tandem relation adjacent the shaft 455 and near the hub 450 (Figs. 5, 30 and 31). The switch 494 is of the single stationary contact type, is normally open, and is disposed in the circuit of the power initiating means of the conveyer mechanism 81. The switch 495 is of the two stationary contact type and alternates between the circuit of the solenoid 424 of the air motor 425 and the circuit of the solenoid 488 of the

air motor 487, normally being operatively closed in the latter circuit. The switches 494 and 495 include rotatable actuating shafts 496 and 497 which are connected by a U-shaped member 498 for simultaneous actuation of the switches 494 and 495. The U-shaped member 498 is disposed in the path of the post 452 of the hub 450 and is adapted to be rotated thereby upon rotation of the shaft 455 by the air motor 487. The electrical circuits of the switches 494 and 495 are detailed below in the description of Fig. 4.

The loaded case receiving and discharge conveyer mechanism 81 is located beneath the table mechanism 78 and between the frame plates 85 and 86 (Figs. 7, 12, 13, 16 and 26 through 29). A pair of spaced shafts 500 is supported on the bottom flange 93 of the frame plate 86, each being secured in vertical position by a bracket 501 which receives the upper end thereof (Figs. 7 and 13). Slidably mounted on the shafts 500 is a conveyer lift casting 502 which may be of aluminum or other metal and is preferably of the form clearly shown in Figs. 28 and 29. The casting 502 includes a U-shaped body portion 503 from one side of the legs of which extend parallel arms 504 and from the other side of which, centrally of the bight, extends a bifurcated lug 505. As is clear from Figs. 7 and 12, the arms 504 extend inwardly from the frame plate 86 and the lug 505 extends outwardly through an elongated slot 506 provided in the frame plate 86.

Power means for reciprocating the casting 502 is provided in the form of a standard commercial solenoid operated air motor 507, mounted on a bracket 508 supported by the frame plate 86, which is pivotally connected to the lug 505 at 509 by a member 510 threadedly engaging the threaded end of the air motor plunger 511. The air motor 507 includes a solenoid 512, the electrical circuit of which is more particularly described below in the description of Fig. 4, which operates the valve of the air motor 507 to move the casting 502 on the shafts 500.

A conveyer 515, preferably of the construction shown in Fig. 26, is supported on the arms 504 of the casting 502. The conveyer 515 includes channel side members 516 from one end of which extend tilting straps 517. Welded to and spacing the side members 516 are end members 518. Intermediate strap members 519 are welded to the end members 518 and are disposed parallel to the side members 516. The intermediate strap members 519 cooperate with the opposed side members 516 to support a plurality of roller studs 520 which are peened over at their ends, or otherwise secured, to prevent accidental removal, each of which supports a freely rotating roller 521. The conveyer 515 rests on both arms 504 of the casting 502 when in the position shown in Fig. 16 in full lines, being pivotally connected to the right-hand arm 504 (looking at Fig. 16) by spaced hinge plates 523 secured to the arm 504 by suitable bolts 524, a hinge pin 525 extending through each side member 516 and through the pintle receiving portion of the associated hinge plate 523 (Figs. 12 and 16).

An arcuate plate 528 of less width than the distance between the intermediate straps 519 of the conveyer 515 is disposed between the straps 519 and forms, in effect, a continuation of the plate 405 of the case guide 80 when the conveyer 515 is in raised position (Figs. 12 and 16). The plate 528 is pivotally supported at the upper ends of two spaced pivot arms 529, the particular configuration of which is shown in Fig. 27, the upper

end of each pivot arm 529 being formed as a bearing sleeve 530 which fits between a pair of brackets 531 welded or otherwise secured to the bottom of the plate 528, being pivotally connected thereto by a suitable connecting pin 532. The pivot arm 529 also includes a centrally located bearing hub 534 and an apertured enlargement 535. Each bearing hub 534 is pivotally mounted on a stub shaft 536 supported by spaced bearing blocks 537 secured to the intermediate straps 519 of the conveyer 515 by welding, or the like, and depending therefrom, as is clear from Fig. 16. A U-shaped conveyer link 538 is pivotally connected at 539 and 540 to the enlargement 535 of the two pivot arms 529. At the juncture of one leg and the bight thereof, the U-shaped conveyer link 538 supports a roller 541. A plate 542 welded to the flanges 93 of the frame plates 85 and 86 and extending therebetween is disposed beneath the roller 541 and limits its downward travel, thereby causing a breaking action of the link 538 and the pivot arms 529 to lower the plate 528 relative to the conveyer 515. A heavy tension spring 544 is connected at one end to a post 545 secured to the forward leg of the link 538 (viewing Fig. 16) and at the other end to an eye member 546 anchored in a strap 547 welded at its ends to the bottom flanges 93 of the frame plates 85 and 86. The spring 544 biases the arcuate plate 528 towards and into raised position above the conveyer 515. An adjustable stop screw 548 threadedly mounted in a strap 549 welded or otherwise secured to the strap members 519 limits counterclockwise movement of the left pivot arm 529, and, hence, determines the upper position of the arcuate plate 528. A compression spring 543 surrounds the bottom portion of each shaft 500, which serve as bumpers for the casting 502.

A switch 550 is supported by a bracket 551 secured to the left-hand intermediate strap 519 of the conveyer 515 (viewing Fig. 12). The switch 550 includes a rotatable actuating shaft 552 to which is secured an arm 553 which extends upwardly between a notch 554 (Fig. 12) provided in the plate 528. The switch 550 is of the movable switch blade two stationary contact type, and is effective to establish a holding circuit for the solenoid 512 when in one position. The electrical circuits of the switch 550 are detailed below in the description of Fig. 4.

A tilting bar 555 is secured by bolts 556 to the vertical flanges 91 of the frame plates 85 and 86 at a point beneath the uppermost position of the tilting straps 517 of the conveyer 515. The tilting bar 555 is contacted by the tilting straps 517 of the conveyer 515 in the downward travel of the conveyer 515 to tilt it to the position shown in broken lines in Fig. 16 to permit a loaded carton 382 to slide to the floor or to an adjacent conveyer platform, or the like, as indicated by the arrow A. It is to be noted that the plate 528 is lowered relative to the conveyer 515, as stated above, as the conveyer mechanism 81 descends, thereby dropping the carton 382 from its raised position shown in full lines in Fig. 16 into contact with the rollers 521 of the conveyer 515.

A main power switch 560 is provided which is mounted on the outer face of the frame panel 85 and which includes "on" and "off" buttons 561 and 562, respectively (Fig. 5). An emergency switch 565 operated by a manual hold-down button 566 is provided to stop the pusher mechanism 73 and the air motor 397 in the event a

bottle 170 tips over, is damaged, or the like (Fig. 5). The switch 565 is mounted adjacent the switch 492 on the bracket 407. The electrical circuits of the switches 560 and 565 are more particularly detailed below in the description of Fig. 4.

Fig. 4 illustrates the electrical circuits of the present machine 78. To the power receiving terminals of the main switch 560 are connected power lines 609. The motor 147 for driving the conveyer chain 136 of the bottle feeding mechanism 72 has one terminal 601 connected to one power take-off terminal 602 of the switch 560 by a lead 603. The other terminal 604 of the motor 147 is connected by a lead 606 to one terminal of the bottle closed normally open switch 165, the other terminal of the switch 165 being connected to the other power take-off terminal 605 of the main switch 560 by leads 607 and 608. As stated above, when the arm 166 of the switch 165 is in the position shown in Fig. 6, the switch 165 is open. The switch 165 is closed to complete the circuit of the motor 147 when power is supplied by the switch 560, when the arm 166 is rotated clockwise, when viewed in plan, as by bottles 170.

The timer reset solenoid 213 has one terminal connected directly to the terminal 602 of the main switch 560 by a lead 610, as connected to the terminal 601 of the motor 147 and to the lead 603, the other terminal of the solenoid 213 being connected by a lead 611 to one terminal of the switch 252. The other terminal of the switch 252 is connected by a lead 609 and the lead 608 to the terminal 605 of the switch 560. Hence, the circuit of the solenoid 213 is controlled by the switch 252 (described in detail above) once power is supplied by closing the main switch 560.

The circuit of the bottle limit switch construction 75 includes a lead 612 which runs from the terminal 602 of the main switch 560 to the terminal 618 of the movable switch blade of the switch 300. The switch 300 includes two stationary contacts 613 and 614, the former of which is connected by a lead 615 to one terminal post 287 at one side of the series of switches 278. The other terminal post 287 thereof is connected by a lead 616 to terminal post 617, which, in turn, is connected by a lead 619 to one terminal 620 of the solenoid 400 of the rack pusher air motor 397. A lead 621 connects the terminal 620 with one terminal 622 of the solenoid 190 of the bottle pusher air motor 191. A lead 623 connects a second terminal 624 of the solenoid 400 with the second terminal 625 of the solenoid 190. A lead 626 connects the terminal 625 with one stationary contact 627 of the switch 240. The terminal 630 of the movable switch blade of the switch 240 is connected by a lead 628 with one terminal 629 of the emergency hold-down switch 555, which is normally closed in circuit making position. The other terminal 631 of the switch 565 is connected by a lead 632 to one stationary contact 633 of the switch 435. The terminal 634 of the movable switch blade of the switch 495 is connected by a lead 635 to the terminal 605 of the main switch 560 to complete the circuit. In addition, the stationary contact 614 of the switch 300 is connected by a lead 636 with the terminal post 617 to provide a holding circuit for the solenoids 190 and 400 during the pushing action of the air motors 191 and 397 after the bottles 170 have passed from engagement by the fingers 290.

The electrical circuit for the solenoid 488 of

the shaft rotating air motor 487 includes a lead 640 between the other stationary contact 641 of the switch 240 and one terminal 642 of the operator's indexing switch 492. The other terminal 643 is connected by a lead 644 to one terminal 645 of the solenoid 488. The other terminal 646 of the solenoid 488 is connected by a lead 647 into the terminal 602 of the main switch 560. The circuit is completed through the aforesaid leads 628, running from the terminal 630 of the switch 240, the terminals 629 and 631 of the switch 565, the lead 632, the fixed contact 633 and the terminal 634 of the switch 495, and the lead 635 which is connected to the terminal 605 of the main switch 560.

The circuit for the solenoid 424 of the air motor 425 which rotates the rotary table mechanism 78 includes a lead 650 connected to the terminal 602 of the main switch 560 and to the terminal 651 of the movable switch blade of the switch 550. The movable switch blade of the switch 550 is normally in contact with one stationary contact 652 which is connected by a lead 653 to one terminal 654 of the solenoid 424. The other terminal 655 of the solenoid 424 is connected by a lead 656 to the other fixed contact 657 of the switch 495. The circuit is completed when the movable switch blade of the switch 495 is in engagement with the fixed contact 657, the said movable switch blade being connected by the lead 635 to the terminal 605 of the main switch 560.

The circuit of the solenoid 512 which actuates the conveyer lowering air motor 507 includes a lead 660 running from the terminal 602 of the main switch 560 to one terminal 661 of the switch 494. The other terminal 662 of the switch 494 is connected by a lead 663 to one terminal 664 of the switch 432. The other terminal 665 of the switch 432 is connected by a lead 666 to one terminal 667 of the solenoid 512. The other terminal 668 of the solenoid 512 is connected by a lead 669 into the lead 635 at 670, the lead 635 being connected to the terminal 605 of the main switch 560. There is provided a holding circuit for the solenoid 512 which includes the lead 650, the movable switch blade terminal 651 of the switch 550, the other fixed contact 671 of the switch 550, and a lead 672 connected to the terminal 671 and to the terminal 667 of the solenoid 512. The holding circuit is completed through the terminal 668 of the solenoid 512, the lead 669, the juncture 670 and the lead 635 to the terminal 605 of the main switch 560.

There is shown in Figs. 56 through 59 a bottle feed control mechanism 700 which may be employed to limit the feed of bottles to the machine 70 to a predetermined number, six as illustrated. A star wheel 701 is secured by setscrews 702 to a vertical shaft 703 pivotally mounted in a bearing block 704 secured by bolts 705 to the outer face of the upper supporting member 132 (viewing Fig. 56). To the lower end of the shaft 703 is secured a ratchet wheel 707 having a single periphery shoulder 708. As is clear from Figs. 56 and 57, the star wheel 701 is disposed between the supporting member 132 and the vertically spaced guide straps 162 in a manner to be contacted by bottles 170 moving along the conveyer 136. The illustrated star wheel 701 includes six concave edges 709 so that six bottles 170 are permitted to pass in one full revolution thereof. A pawl 711 is pivotally mounted by a nut and bolt assembly 712 on a bracket 713 secured to the supporting member 132 by suitable bolts 714. The

pawl 711 is in the plane of the ratchet wheel 707 and has the free end biased into engagement with the periphery thereof for engagement with the shoulder 708 by a tension spring 715 which has one end secured to a pivot post 716 mounted in the pawl 711 intermediate its ends and the other end to a U-shaped bracket member 717 secured by suitable bolts 718 to the supporting members 132. A solenoid 720 is supported beneath the members 132 on a bracket 721 adjustably secured by bolt and slot connections 722 to the supporting members 132. The solenoid 720 includes a reciprocating core 725 having an external head 726 to which is pivotally connected at 727 a link 728. The link 728 is connected to the pivot post 716 mounted in the pawl 711. Leads 730 connect the solenoid 720 with a make-and-break switch located on the pusher mechanism 73 in a position to be closed by any convenient element thereof as the air motor 191 completes its pushing stroke. Closing of this control switch energizes the solenoid 720 to effect withdrawal of the pawl 711 from engagement with the shoulder 708 of the ratchet wheel 707, which will permit six bottles to pass the star wheel 701. It is to be understood that the control switch for the solenoid 720 is maintained closed only a short period of time and is then opened as by spring action so that the pawl 711 can return under the influence of the spring 715 to engagement with the periphery of the ratchet wheel 707 to contact the shoulder 708 as one revolution is completed to insure only six bottles 170 passing the star wheel 701.

Operation

The operation of the present machine 70 is apparent from the detailed description given above of the several mechanisms which combine to provide the instant novel case loader, particularly when the electrical circuits traced in detail in the description of Fig. 4 are borne in mind. However, a sequential over-all description of the operation of the machine 70 is helpful for a complete appreciation of the novelty incorporated.

It is to be understood that the necessary compressed air is available and ready for operation of the cylinders of the several air motors which are employed in effecting motion of the several mechanisms combined in the machine 70.

To initiate case loading operation of the machine 70, the main switch 560 is closed by pushing the button 561 inwardly, the electrical power supplied from the main lines 600 remaining on until the push button 562 is moved inwardly to stop the machine. The motor 147 is immediately energized to move the conveyer chain 136, it being assumed that the conveyer chain 136 is full of bottles to a point entering the machine 70 which will result in the arm 166 of the switch 165 being rotated outwardly to close the switch 165.

The bottles 170 will proceed into the machine 70 on the conveyer chain 136 until the six bottles 170 are in the positions of Fig. 14, thereby closing the six switches 278 through pivotal movement of the switch fingers 290. The bottle stop 76 limits inward movement of the bottles 170, as indicated. The moment the last switch 278 is closed, the circuit through the solenoid 190 of the air motor 191 of the pusher mechanism 73 and the solenoid 400 of the air motor 397, which moves the continuous belts 364, is complete and the said solenoids 190 and 400 are energized to initiate pushing action of the air motors 191 and 397, respectively. Thereupon the pusher mechanism 73 pushes the six bottles 170 transversely from

the conveyer chain 136 onto the six belts 364 of the rotary table mechanism 78, which are meanwhile being moved in the direction of movement of the bottles 170 by the air motor 397. It is to be noted that the solenoid 190 raises the bottle guide mechanism 74 in the same movement of opening the air valve of the air motor 191, so that the bottle guide member 263 moves out of the path of the bottles 170 in timed relation to their transverse movement onto the belts 364.

As the pusher mechanism 73 moves forwardly, the arm 301 of the switch 300 is tripped by the trip finger 302 of the trip member 303 secured to the pusher shaft 179, which results in movement of the switch blade of the switch 300 from engagement with the stationary contact 613 to engagement with the stationary contact 614 (Fig. 4), thereby breaking the circuit through the switches 278 but energizing the holding circuit through the solenoids 190 and 400, a necessary action to hold the circuit closed until the air motors 191 and 397 complete their strokes, since otherwise the circuit through the solenoids 190 and 400 would be broken as the bottles 170 clear the ends of the switch fingers 290 of the switches 278. As the pusher mechanism 73 reaches a predetermined point near the end of its stroke, the arm 301 slips from engagement with the trip finger 302 and returns under spring action to its normal position in which the switch blade of the switch 300 engages the stationary contact 613, thereby breaking the holding circuit and deenergizing the solenoids 190 and 400 to reverse the action of the air motors 191 and 397.

The air motors 191 and 397 return to starting positions, the air valves thereof changing position to effect same under spring action on deenergization of the solenoids 190 and 400, and six more bottles move into the machine 70. Bottles are prevented from entering the machine 70 by the flanges 189 of the pusher plate 184 while the pusher mechanism 73 is operating, although the conveyer chain 136 continues to move. The cycle is repeated until four rows of six bottles each are in position on the belts 364 of the rotary table mechanism 78, which constitute a charge or group of bottles for the present machine 70. On the return stroke of the air motor 397, after the fourth row of bottles 170 has been moved onto the belts 364, the finger 246 of the limit wheel 244 of the timer mechanism 77 engages the roller 242 of the plunger 241 of the switch 240, thereby moving the switch blade thereof from engagement with the stationary contact 621 to engagement with the stationary contact 641 and breaking the circuit through the solenoids 190 and 400 of the air motors 191 and 397, respectively, to prevent further pushing action until the switch 240 is reversed as to the position of its switch blade. Hence, while six more bottles move into the machine 70 and close the switches 278, no pushing operation thereof ensues, since the circuit is open at the switch 240.

The machine attendant places the carton 382 with its separators 383 in inverted position over the bottles 170 on the belts 364, with the flaps thereof along three sides on the flap holders 381. The attendant then pushes the button 493 of the switch 492 to index the machine 70 and to complete the steps of one case loading cycle. The pushing of the button 493 closes the circuit through the solenoid 488 of the air motor 487, which thereupon is actuated to rotate the shaft 455. The locating pin 440 is pulled from engage-

ment with the opening 438 of the ratchet wheel 435, and at the same time the U-shaped member 498 connected to the actuating shafts 496 and 497 of the switches 494 and 495 is rotated by the post 452 of the locating pin operating arm 447 engaging the same. The switch 494 is thereby opened to insure that the circuit of the conveyer mechanism remains open. The switch 495 is actuated to move its switch blade from engagement with the stationary contact 633 to engagement with the stationary contact 657, which opens the circuit through the solenoid 488 and permits the return stroke of the air motor 487 and the return rotation of the shaft 455.

The aforesaid movement of the switch blade of the switch 495 also closes the circuit through the solenoid 424 of the air motor 425, and hence the air motor 425 is actuated to rotate the rotary table mechanism through 180°, at the completion of which the locating pin 440 snaps into the aligned opening 438 of the ratchet wheel 435 under the influence of the spring 459.

The actual loading of a predetermined plurality of bottles 170 into a carton 382 is clearly indicated by Figures 5 and 16, which respectively show the relationship between the rotary table mechanism 78, the bottles 170, and the carton 382 before and after the indexing operation. From a comparison of these figures, it is apparent that the 180° movement of the mechanism 78 carries the carton 382 around the concave surfaces of the arcuate plates 405 and 528, these plates serving to maintain the carton 382 in fixed relation with the mechanism 78 during the rotating movement of the latter. As the bottles 170 are inverted along with the mechanism 78, they receive lateral support from the partition plates 321 and are thus guided into appropriate cells in the carton 382 as shown in Figure 16.

As the air motor 425 reaches the end of its stroke, the crank arm 420 engages the arm 433 of the switch 432 to close the switch 432. At about the same time, the U-shaped member 498 is released by the post 452 of the locating pin operating arm 447, so that the switch 494 is closed and the switch blade of the switch 495 is moved from engagement with the stationary contact 657 into engagement with the stationary contact 633.

The circuit through the solenoid 512 of the air motor 507, which lowers the conveyer mechanism 81, is now closed since both switches 432 and 494 are in closed positions. Thereupon the air motor 507 functions to lower the conveyer mechanism 81 with its now upright carton 382 filled with bottles 170 in inverted or neck-down positions. As the conveyer 515 moves down on the casting 502, the tilting straps 517 thereof engage the tilting bar 555 secured to the frame plates 85 and 86, thereby effecting a hinged tilting action of the conveyer 515 about the hinge pins 525 as the casting 502 continues its downward travel. As the filled carton 382 rolls from the conveyer 515, it strikes the arm 553 of the switch 550 to establish a holding circuit for the solenoid 512 until the carton 382 is clear of the machine 70. Movement of the arm 553 moves the switch blade of the switch 550 from engagement with its fixed contact 652 to engagement with its fixed contact 671, thereby at the same time breaking the circuit through the solenoid 424 of the air motor 425 to permit reverse action thereof and to prevent indexing action until the arm 553 is released. The said holding circuit is

necessary since the switch 432 is opened under spring action of the arm 433 as the air motor 425 returns to starting position. As soon as the carton 382 clears the machine 70, the arm 553 snaps back to initial position to break the holding circuit and to reestablish contact of the movable switch blade of the switch 550 with the stationary contact 652, thereby permitting the air motor 507 to reverse to return the conveyer 515 to its raised position. The spring 544 returns the arcuate plate 528 to the raised position of Fig. 16.

It is to be observed that, each time the rotary table mechanism 78 indexes, the trip plates 255 energize and deenergize the solenoid 213. As the rotary table mechanism 78 begins its 180 degrees of rotation, one trip plate 255 of the trip device 256 immediately adjacent the roller 254 at the end of the plunger 253 of the switch 252 is engaged to close the circuit of the switch 252. Thereupon the solenoid 213 is energized to pivot the stop pawl 220 from engagement with the ratchet wheel 224, the pivotal movement of which, through its lift pin 251, also raises the pawl 230 from engagement with the ratchet wheel 224. The ratchet wheel 224 and the limit wheel 244 immediately return to initial starting position under spring action, thereby releasing the plunger 241 of the switch 240 which, under spring action, moves outwardly and effects movement of the switch blade of the switch 240 from engagement with the contact 641 to engagement with the contact 627, thereby breaking the circuit through the switch 492 and preventing another indexing action until the switch blade of the switch 240 is again in contact with the stationary contact 641. The circuit through the solenoids 198 and 409 is again thereby completed and the pushing action of the air motors 191 and 397 is again initiated to start another case loading cycle, which is timed to begin as the table mechanism 78 completes its 180 degrees of rotation and before the previously loaded carton is clear of the machine 70, to utilize all available time. Hence, there is an overlapping cycle. The solenoid 213 is deenergized as the rotary table mechanism 78 completes its 180 degrees of rotation by the first trip plate 255 of the trip device 256, originally remote, striking the plunger 253 of the switch 252 to open the circuit thereof, which releases the stop pawl 220 and the pawl 230.

The emergency switch 565 is available for stopping pushing action of the air motor 191 and the air motor 397 should a bottle fall over or break or should it be necessary for any other reason to stop the pushing action of the machine 70 for a short period of time. The switch 565 is of the type that requires the button 566 to be kept pushed in to maintain the circuit interrupted. Release of the button 566 again completes the circuit and the pushing action continues.

It is apparent that there has been provided a novel packaging machine which fulfills all of the objects and advantages sought therefor, and a novel method of packing bottles, and other articles, in containers in inverted positions.

It is to be understood that the foregoing description and the accompanying drawings have been given by way of illustration and example. It is also to be understood that changes in form of the several parts, substitution of equivalent steps and elements, and rearrangement of steps and parts, which will be readily apparent to one skilled in the art, are contemplated as within

the scope of the present invention, which is limited only by the claims which follow.

What is claimed is:

1. In combination, a rotary table mechanism for packaging machines comprising a horizontal shaft, a main body secured to said shaft for rotation therewith, said main body being symmetrical about a horizontal axial plane, a series of upper endless belts above said horizontal axial plane and a series of lower endless belts below said horizontal axial plane supported by said main body for endless travel, the particular series of endless belts in upper position forming a horizontal table for receiving bottles and the like in upright position thereon, means for moving the particular series of upper belts by predetermined increments, means for rotating said main body through half-revolution increments to reverse the positions of said series of upper and lower belts, and partition means secured to said main body between adjacent belts thereon for preventing tipping of bottles relative to said belts upon rotation of said main body.

2. In combination, conveyer mechanism for packaging machines for receiving a loaded carton and moving it from received position, comprising a vertically reciprocable carrier member, means supporting said carrier member for reciprocable movement, means for reciprocating said carrier member, a conveyer member supported by said carrier member and hingedly connected thereto, means pivotally supported by and above said carrier member for initially receiving a loaded carton, means operative during downward movement of said carrier member for pivotally lowering said last-named means towards said carrier member to bring a received carton into contact with said carrier member, and means for tipping said conveyer member during its downward movement to move a received carton therefrom by gravity.

3. In combination, mechanism for assembling a group of bottles on a provided table in rows comprising an endless chain conveyer, a bottle stop to limit bottle travel, a bottle guide to prevent tipping of bottles, pusher mechanism including a reciprocable plate of a length to push a row of bottles transversely from said chain conveyer and power means for reciprocating said plate, a solenoid for actuating said power means, said solenoid being connected to said bottle guide to move it from bottle guiding position as the power means is actuated, means for energizing said solenoid including a plurality of switches in series, each switch having an arm for contact by a bottle to close the same, said solenoid being energized when all of said switches are closed and its circuit is otherwise closed, a holding circuit for maintaining said solenoid energized after release of said switch arms by bottles being pushed from said chain conveyer, a switch for interrupting the solenoid circuit, and timer mechanism for opening said interrupter switch when a predetermined number of bottles have been moved from the chain conveyer.

4. A packaging machine comprising, in combination, a frame, a conveyer mechanism including an endless chain for moving bottles and the like into the machine, a rotatable table mechanism mounted on the frame and disposed adjacent a portion of said chain, a stop member for limiting movement of conveyed bottles beyond a predetermined point opposite said table mechanism, a bottle guide for preventing tipping of bottles being moved into position op-

posite said rotatable table mechanism, a pusher mechanism supported by said frame including a reciprocable plate for pushing bottles from said chain onto said table mechanism, means for actuating said pusher mechanism controlled by bottles on said chain, said table mechanism including a plurality of endless belts for receiving bottles pushed from the chain, means for moving said belts in increments in timed relation to movement of bottles from the chain onto said belts, said table mechanism including means for providing lateral support to each bottle disposed thereon thereby to prevent tipping of bottles relative to the table mechanism upon rotation of the latter, said table mechanism further including means for supporting a bottle container in inverted position above bottles thereon, means for rotating said table mechanism through half-revolution increments, means for maintaining a container in substantially initial position relative to said table mechanism during rotation so that bottles grouped on the table mechanism are moved into the container in inverted positions, a vertically reciprocable conveyer mechanism disposed beneath said table mechanism for receiving a righted loaded container, and means for actuating said conveyer mechanism to remove a received loaded container from the machine.

5. A packaging machine comprising, in combination, a frame, a conveyer mechanism including an endless chain for moving bottles and the like into the machine, power means for continuously moving said chain, a rotatable table mechanism mounted on the frame and disposed adjacent a portion of said chain, a stop member for limiting movement of conveyed bottles beyond a predetermined point opposite said table mechanism, a bottle guide for preventing tipping of bottles being moved into position opposite said rotatable table mechanism, a pusher mechanism supported by said frame including a reciprocable plate for pushing bottles from said chain onto said table mechanism and power means to which said plate is connected, means for actuating said pusher mechanism power means controlled by bottles on said chain including a solenoid and electrical circuit, said bottle guide being connected to said solenoid for bottle clearing movement prior to movement of said plate, said table mechanism including a plurality of endless belts for receiving bottles pushed from the chain, means for moving said belts in increments in timed relation to movement of bottles from the chain onto said belts including a solenoid actuating means in series with said first solenoid, means for interrupting the circuit through the solenoids to prevent further pusher action upon a predetermined number of pushing actions being completed, said table mechanism including means for providing lateral support to each bottle disposed thereon thereby to prevent tipping of bottles relative to the table mechanism upon rotation of the latter, said table mechanism further including means for supporting a bottle container in inverted position above bottles thereon, means for rotating said table mechanism through half-revolution increments, means for maintaining a container in substantially initial position relative to said table mechanism during rotation so that bottles grouped on the table mechanism are moved into the container in inverted positions, means actuated by said rotary table mechanism for releasing the interrupter means to permit further pusher action in timed relation to the

completion of 180° of rotation by said rotary table mechanism, a vertically reciprocable conveyer mechanism disposed beneath said table mechanism for receiving a righted loaded container, and means for actuating said conveyer mechanism to remove a received loaded container from the machine.

6. A packaging machine comprising, in combination, a frame, a conveyer mechanism associated therewith and including an endless chain for moving bottles into said machine, power means for continuously driving said endless chain, a rotary table mechanism supported on the frame and disposed adjacent a portion of said chain including a table for bottles and supports for an inverted carton, a stop member limiting bottle travel on said chain to positions opposite said table mechanism, a bottle guide for preventing tipping of bottles moved into said machine, a pusher mechanism for moving bottles from said chain onto said rotary table mechanism including a pusher plate of width to push a predetermined number of bottles, power means for reciprocating said plate, and a solenoid for actuating said power means, means connecting said bottle guide to said solenoid for timed movement of the former to clear bottles as the pusher mechanism operates, a plurality of normally open switches in series with said solenoid disposed along said chain, each switch including an arm adapted to be rotated by a bottle to close the switch, timer mechanism for opening the circuit through the said solenoid after a predetermined number of pusher actions by the pusher mechanism, power means for rotating the rotary table mechanism and a solenoid for actuating the same, indexing mechanism for limiting the rotary table mechanism to half-revolution increments including power means for releasing said mechanism to permit rotation and a solenoid for actuating the same, normally open electrical circuits through said indexing mechanism solenoid and said rotary table mechanism solenoid, means for closing the circuit through said indexing mechanism solenoid circuit, normally open switch means in said rotary table mechanism solenoid circuit actuated by said indexing power means for closing the said circuit, means actuated by said rotary table mechanism for releasing the timer mechanism when holding the pusher mechanism solenoid circuit open to restore the same, means for providing lateral support to each bottle disposed on the rotary table mechanism thereby to prevent tipping of bottles relative thereto upon rotary movement thereof, means for holding an inverted carton in place on the rotary table mechanism during rotation thereof so that bottles on the same are moved into the carton in inverted position, a conveyer mechanism beneath the rotary table mechanism including a tiltable loaded carton receiving conveyer, power means for lowering the conveyer to tilt the same, and a solenoid for actuating the power means, the circuit through the last-named solenoid being normally open, normally open switch means in the conveyer mechanism solenoid circuit closed by the power means of the rotary table mechanism to energize the said conveyer mechanism solenoid, said last switch adapted to be opened as the said power means which closed it returns toward starting position, a holding circuit for maintaining the circuit through the conveyer mechanism solenoid closed until a received carton is free thereof including a switch which in one position closes the

holding circuit and opens the indexing circuit against normal closing and in its normal released position continues the indexing circuit for normal closing and opens the said holding circuit, and a main switch for closing and opening a provided source of electrical power to said machine for the sequential operation thereof.

7. In combination, a rotary article receiving table mechanism for packaging machines comprising a main body, means mounting said main body for rotation about a horizontal axis, said main body being symmetrical about a horizontal axial plane and being adapted to receive articles when in either of two positions one hundred and eighty degrees of rotation apart, two opposed series of endless belts forming alternately operable article receiving means, said two series of endless belts being on opposite sides of said horizontal axial plane so that one series of endless belts forms an upwardly facing horizontal table-like article receiving means while the other series of endless belts is in downwardly facing inoperative position, a plurality of partition plates disposed on said main body in parallel relation with said belts for providing a lateral support to articles received on the latter during a subsequent rotation of said mechanism, means for moving the particular upper series of endless belts in timed spaced increments determined by the diameter of the received articles, and means for rotating said mechanism through 180° after a predetermined number of incremental movements of the particular upper series of endless belts.

8. In combination, conveyer mechanism for packaging machines for receiving a loaded carton and moving it from received position, comprising a vertically reciprocable carrier member, means supporting said carrier member for reciprocable movement, power means for reciprocating said carrier member, a conveyer member supported by said carrier member and hingedly connected thereto, means pivotally supported by and above said carrier member for initially receiving a loaded carton, means operative during downward movement of said carrier member for pivotally lowering said last-named means towards said carrier member to bring a received carton into contact with said carrier member, means for tipping said conveyer member during downward movement to move a received carton therefrom by gravity, and means for preventing the power means from returning the carrier member to carton receiving position until a previously received carton has cleared said conveyer member.

9. In combination, conveyer mechanism for packaging machines for receiving a loaded carton and moving it from received position, comprising a vertically reciprocable carrier member, means supporting said carrier member for reciprocable movement, means for reciprocating said carrier member, a conveyer member supported by said carrier member and hingedly connected thereto, means pivotally supported by and above said carrier member for initially receiving a loaded carton, means operative during downward movement of said carrier member for pivotally lowering said last-named means towards said carrier member to bring a received carton into contact with said carrier member, means for returning said pivotally supported means to initial carton receiving position as said carrier member is returned to initial position, and means for tipping said conveyer member during downward

movement to move a received carton therefrom by gravity.

10. In combination, in an article packaging machine, mechanism for receiving packed cartons from said machine and for discharging such received packed cartons therefrom, comprising a conveyer member, means supporting said conveyer member for vertical reciprocative and tilting movement, means for effecting vertical reciprocative movement of said conveyer member supporting means, said conveyer member having an initial upper position for receiving packed cartons from the machine, means for tilting said conveyor member during descending movement to permit a carton to discharge therefrom by gravity, means for preventing return of said conveyer to initial position until a supported packed carton is completely discharged therefrom, said latter means comprising control means operatively connected with said means for effecting vertical reciprocative movement of said conveyor member supporting means, and a movable actuating member on said control means adapted to be actuatingly displaced by a received carton from the time of receipt thereof until discharge of the same.

11. A packaging machine comprising, in combination, a frame, an invertible table mechanism supported on said frame including movable means formed for receiving thereon a group of bottles in formation for filling a packaging container, means for supplying successive rows of bottles in positions for movement onto said movable means including a bottle support adjacent said table mechanism, means for pushing a row of bottles onto said movable means from said support, means for moving said movable means simultaneously with said pusher means to assist movement of each row of bottles thereon from said support and to move previously received bottles further away from said support and into packaging positions, means for packaging each predetermined group of received rows of bottles including means for inverting said table mechanism, and means for rendering said inverting means operative following movement onto said movable means of said predetermined group of rows of bottles.

12. In a packaging machine, in combination, a frame, a table mechanism supported by said frame including a plurality of flexible endless belts disposed in parallel arrangement for receiving and supporting bottles on the upper runs thereof, means slidably supporting said upper runs in a substantially horizontal plane for maintaining bottles in erect position thereon, means for moving said belts simultaneously and in predetermined increments of movement, means for moving bottles into positions in a row adjacent one set of ends of said belts including a support for the bottles adjacent said ends, means for pushing a row of bottles onto said belts from said support, and means for simultaneously actuating said bottle pushing means and said means for moving said belts, said bottle pushing means and said means for moving said belts cooperating when actuated to move a row of bottles onto the belts in a manner minimizing overturning, said means for moving said belts when actuated also moving simultaneously as a compact group bottles previously disposed on said belts out of the way of bottles being pushed and into packaging positions.

13. The packaging machine combination as set forth in claim 12 and including timer means

for rendering inoperative both said pusher means and said means for moving said belts following a predetermined number of movements of said two means in moving rows of bottles onto said table mechanism, and means for automatically restoring said two means to operative condition following predetermined additional packaging operations completing a full operational cycle by said machine.

14. In a packaging machine, in combination, a frame, a rotary table mechanism rotatably mounted on said frame including upper and lower surfaces for receiving bottles in predetermined groups for packaging, means for loading the upper disposed surfaces thereof with a charge of bottles for packaging, power actuated means for rotating said table mechanism through increments of one hundred eighty degrees of rotation, locating means for maintaining said table mechanism in bottle receiving position against rotation and for stopping the same in the next bottle receiving position upon release and rotation thereof including electrically energizable power means for releasing said locating means, means for supporting a packaging carton on the table mechanism over a charge of bottles, means affording lateral support for each bottle of a charge thereof during rotation of said table mechanism whereby to prevent tipping of bottles relative to said bottle receiving surfaces, and means for maintaining a packaging carton in position during rotation of said table mechanism to permit a charge of bottles to slide thereinto in inverted positions.

15. The packaging machine combination of claim 14 in which said locating means includes a member secured to and rotatable with said table mechanism having diametric openings therein and a pivotally mounted plunger member spring biased into register with one of said openings, said electrically energizable power means being mechanically connected to said plunger member for retraction thereof from the engaged opening upon energization thereof, and means for deenergizing this power means prior to completion of rotation of said table mechanism through one hundred eighty degrees to permit register of said plunger member with the other opening.

16. The packaging machine combination of claim 14 and including power actuated means for moving rows of bottles onto the upper surface of said table mechanism, and means for rendering said bottle moving power actuated means inoperative upon movement onto said upper surfaces of said table mechanism of a predetermined number of rows of bottles and for sequentially rendering operative said power actuated rotating means so that said two power actuated means cannot be operated simultaneously.

17. In a packaging machine, in combination, a frame, a rotary table mechanism rotatably mounted on said frame including a plurality of surfaces for receiving individual charges of bottles to be packaged, said surfaces being equally angularly spaced about the axis of rotation of said table mechanism, power actuated means for moving bottles onto a bottle receiving surface of said table mechanism, power actuated means for rotating said table mechanism through angular increments to package a charge of bottles, said table mechanism including spaced elements disposed parallel to said axis of rotation adapted to provide lateral support to each bottle of a charge thereof during rotation of the mechanism,

said two power actuated means being sequentially operative, means for rendering said first mentioned power actuated means inoperative following completion thereby of a predetermined number of bottle loading movements and for sequentially rendering said second mentioned power means operative, and means for rendering said second mentioned power means inoperative upon rotation thereby of said table mechanism through the predetermined angle of movement and sequentially rendering said first mentioned power means operative.

18. In a packaging machine, in combination, a frame, a table mechanism supported by said frame including a plurality of flexible endless belts disposed in parallel arrangement for receiving and supporting bottles on the upper runs thereof, means slidably supporting said upper runs in a substantially horizontal plane for maintaining bottles in erect position thereon, means for moving said belts simultaneously and in predetermined increments of movement, means for moving bottles into positions in a row adjacent one set of ends of said belts including a support for the bottles adjacent said ends, means for pushing a row of bottles onto said belts from said support, and means for simultaneously actuating said bottle pushing means and said means for moving said belts, said bottle pushing means and said means for moving said belts cooperating when actuated to move a row of bottles onto the belts in a manner minimizing overturning, said means for moving said belts when actuated also moving bottles previously disposed on said belts out of the way of bottles being pushed and into packaging positions, said bottle pushing means including an electrically energizable power unit for actuating the same, said means for moving said belts also including an electrically energizable power unit for actuating the same, said simultaneous actuating means including a plurality of switches each having a switch arm engageable by a bottle on said support, there being a switch and a switch arm for closing engagement by each bottle in the row to be pushed onto said belts, said two power units and said plurality of switches being in a common circuit, said two power units being simultaneously energizable upon the closing of all bottle operated switches.

19. In a packaging machine, in combination, a frame, a table mechanism supported by said frame including a plurality of flexible endless belts disposed in parallel arrangement for receiving and supporting bottles on the upper runs thereof, means slidably supporting said upper runs in a substantially horizontal plane for maintaining bottles in erect position thereon, means for moving said belts simultaneously and in predetermined increments of movement, means for moving bottles into positions in a row adjacent one set of ends of said belts including a support for the bottles adjacent said ends, means for pushing a row of bottles onto said belts from said support, means for simultaneously actuating said bottle pushing means and said means for moving said belts, said bottle pushing means and

said means for moving said belts cooperating when actuated to move a row of bottles onto the belts in a manner minimizing overturning, said means for moving said belts when actuated also moving bottles previously disposed on said belts out of the way of bottles being pushed and into packaging positions, movable bottle guide means supported by said frame for preventing overturning of bottles as they are moved into position opposite said belts, and means for moving said guide means from guiding relation with a row of bottles before said pushing means is moved into bottle engaging relation.

20. In a packaging machine, in combination, a frame, a table mechanism supported by said frame including a plurality of flexible endless belts disposed in parallel arrangement for receiving and supporting bottles on the upper runs thereof, means slidably supporting said upper runs in a substantially horizontal plane for maintaining bottles in erect position thereon, means for moving said belts simultaneously and in predetermined increments of movement, means for moving bottles into positions in a row adjacent one set of ends of said belts including a support for the bottles adjacent said ends, means for pushing a row of bottles onto said belts from said support, means for simultaneously actuating said bottle pushing means and said means for moving said belts, said bottle pushing means and said means for moving said belts cooperating when actuated to move a row of bottles onto the belts in a manner minimizing overturning, said means for moving said belts when actuated also moving bottles previously disposed on said belts out of the way of bottles being pushed and into packaging positions, said table mechanism including two sets of endless belts and being substantially symmetrical on each side of a horizontal plane, said table mechanism being mounted upon said frame for rotary movement about a horizontal axis, means for supporting a packaging carton on said table mechanism over a group of bottles thereon, means for rotating said table mechanism through increments of one hundred eighty degrees of rotation, and means for maintaining a packaging carton in engagement with bottles on said table mechanism during rotation thereof to permit bottles to slide thereinto in inverted positions.
